UNITED STATES PATENT OFFICE

JOSEPH A. FIRSCHING, OF UTICA, NEW YORK

APPARATUS FOR DYEING TEXTILE FABRICS

Application filed September 23, 1929. Serial No. 394,523.

This invention relates to an apparatus for dyeing textile fabrics.

In dyeing skeins of textile material which are to be knit into a finished fabric it is desirable for the purpose of producing a particular type of fabric to have the skeins dyed only in certain parts thereof so that when the fabric is completed the color will appear in the fabric only in isolated instances. This type of dyeing is known in the trade as random dyeing and has in the past been accomplished in different ways, as for example, tying a skein into a knot and dipping it into a dye so that certain portions of the skein would be exposed to the dye and certain portions would be protected from it. Another method is to touch the skein intermittently with a dye as the skein is moved along the dyeing apparatus.

The limitations of the two just described methods of random dyeing and of all other methods known to the art are first, that they are limited to the use of one color and second, that the portion of the skein which is dyed is dyed a uniform color, that is to say it is impossible to have parts of the skein more heavily dyed than other parts.

The main object of my invention is to devise a means for random dyeing which will permit the use of a multiplicity of colors on a single skein without having the different colors touch the same portion of the skein.

Another object is to devise a method of random dyeing which will permit the portion of the skein receiving the dye to be more heavily dyed in one part than in another.

Other objects and advantages relate to the size, shape and arrangement of parts of the apparatus here described, all as will more fully appear from the following description taken in connection with the accompanying drawings in which:

Figure 1 is a top plan view of my dyeing machine.

Figure 2 is an end elevation of the machine.

Figure 3 is a section, partially broken away, on line 3—3, Figure 1.

Figure 4 is a section, partially broken away, on line 4—4, Figure 1.

Figure 5 is a section on line 5—5, Figure 2.

Figure 6 is a section on line 6—6, Figure 1. Figure 7 is a section on line 7—7, Figure 1.

Figure 8 is an elevation, partially broken away, of one of my operating levers taken in the plane of the line 8—8 of Figure 4.

Figure 9 is an enlarged view similar to Figure 6, omitting the skein of fabric.

Figure 10 is a plan view of a piece of fabric knitted from textile material which has been dyed by my apparatus, part only of the woof threads being shown.

Referring first to Figures 2 and 4, my apparatus consists of an end frame 1 and a second end frame 2 in spaced relation thereto. The lower parts of end frames 1 and 2 are held in fixed relation by means of transverse tie rods 3 and 4.

On the upper ends of end frames 1 and 2, I secure, as by bolts 5 and 6, a header 7. Header 7 is provided with a plurality, in this case shown as six, of longitudinally extending dye troughs 8. Above dye troughs 8, I provide a grille 9 preferably having openings 11—11 (see Figure 1) non-uniform.

Grille 9 carries on its upper surface, a facing 10 preferably made of a material with some degree of inherent resiliency such as sponge rubber.

The upper face of facing 10 is formed with beveled edges at each opening in grille 9 sloping downwardly thereto as perhaps may best be seen from Figure 9.

Each of the dye troughs 8 has an inclined bottom, at the lower end of which is provided a filler funnel 12 beneath which is positioned a drain or dump valve 13.

On each longitudinal edge of header 7, I provide a plurality, in this case shown as sixteen, vertically movable pins 14 in spaced relation and for a purpose hereinafter to be described.

Pins 14 are carried by a supporting bar 15 and extend upwardly through apertures 18' in header 7.

The construction and mode of operation of the actuating apparatus for pins 14 is the same for each set of pins so that a description of one will serve for a description of the other.

Referring to Figure 3, it will be seen that bar 15 carries a depending link 16 connected

to a bell crank 17 which is mounted on a shaft 18. The opposite end of bell crank 17 is connected by means of a link 19 to the lower end of a lever 20.

5 A laterally extending supporting arm 21 is secured on one side of header 7 as by rivets not shown and a complementary supporting arm 23 is secured to the other side of header 7, as by rivets 24.

10 A shaft 25 is journaled in arms 21 and 23. Lever 20 is splined or otherwise secured on one end of shaft 25 so that the movement of lever 20 will cause a rocking movement of shaft 25, shaft 25 functioning as a pivot for 15 lever 20.

15 On shaft 25 I provide a plurality, in this case shown as six, of laterally extending fingers 26 so positioned that a finger 26 is adapted to contact with and close a drain 20 valve 13 when the shaft 25 is rotated by means of lever 20.

20 I provide on lever 20 a laterally extending latch 27 carrying notches 28 and 29 which are adapted to engage a pin 30 which is carried 25 on a vertically extending side bar 31. Side bar 31 has its lower end secured to supporting arm 21 and is held securely in position by means of a brace 32 which extends diagonally downward and is secured to header 7 by 30 rivets 22.

35 In Figure 3, I have shown lever 20 in the vertical position with notch 29 in engagement with pin 30. In this arrangement of parts, fingers 26 will be in contact with valves 13 to hold such valves closed and supporting bars 15 carrying pins 14 are in the raised position, the pins extending upwardly above the upper surface of header 7.

40 When the latch 27 is raised to permit the movement of lever 20, lever 20 is moved inwardly to bring the notch 28 in registration with the pin 30.

45 This movement of lever 20 will cause the rotation of shaft 25 and this movement of shaft 25 will carry fingers 26 downwardly and out of registration with valves 13 to permit such valves to open. This inward movement of the upper end of lever 20 will cause the outward movement of the lower 50 end thereof which will, through link 19 cause bell crank 17 to be moved about its pivot 18 and this movement of bell crank 17 will through link 16 cause bar 15 to be moved downwardly carrying with it pins 14 to a 55 position where the upper ends of pins 14 are approximately flush with the upper surface of header 7.

60 I have here described only one bar 15, one link 16 and one bell crank 17, but it will be understood that the companion bar 15' on the opposite end of header 7 is provided with a link 16' and a bell crank 17' keyed to shaft 18, and inasmuch as bell crank 17 is also keyed to shaft 18 the movement of bell crank 17 65 through link 19 and lever 20 will cause the

rotation of shaft 18 which in turn will cause the movement of bell crank 17' and through link 16' of plate 15'.

For the purpose of guiding bar 15 in its vertical movement, I provide vertical bars 70 33 and 34 in spaced relation, the upper ends of such vertical bars 33 and 34 being secured to the under side of header 7 and their lower ends being secured to a cross bar 35 on the end frame 2.

A guide bar 36 has its upper end secured to the under surface of bar 15 and carries on its lower end, a laterally extending arm 37 slidably mounted on bar 33.

A similar guide bar 38 is secured to the under surface of bar 15 in spaced relation to bar 36 with a laterally extending arm 39 slidably mounted on bar 34.

Bar 15' is provided with a similar guiding means consisting of vertical bars 40 and 41 85 with upper ends secured to the under surface of header 7 and with their lower ends secured to a cross bar 42.

A guide bar 43 is slidably mounted on bar 40 and has its upper end secured to the under surface of bar 15'. An opposed guide bar 44 is slidably mounted on bar 41 with its upper end secured to the under surface of bar 15'.

90 Referring to the vertically extending side bar 31, I provide a companion vertically extending side bar 45 having its lower end secured to bar 23 and being held securely in position by a brace 46 which extends downwardly and inwardly from bar 45 and is secured to header 7 as by bolts 47.

95 The upper ends of bars 31 and 45 are tied together by means of a shaft 48 on which shaft 48 is rotatably mounted a pulley 49 for a purpose hereinafter to be described.

100 A U-shaped hinge bar 50 has the end of one arm pivotally mounted on bar 31 with a loose fit on its pivot. The opposite arm of hinge bar 50 is pivotally mounted on bar 45 with a loose fit on its pivot.

110 Secured to the inner end of hinge bar 50 as by rivets 51, I provide a pressure plate 52 carrying a grille 53 of a size and shape to register with grille 9 on header 7. The under face of grille 53 carries a facing 54 similar in construction to facing 10 carried on grille 9 and having its edges beveled in opposite directions to the bevels on facing 10.

115 By virtue of hinge bar 50, pressure plate 52 may be raised and lowered with respect to header 7 and to assist in the raising and lowering movement of pressure plate 52, I provide a cable 55 having one end secured to the outer end of pressure plate 52 as by a clamp 56.

120 Cable 55 extends from clamp 56 to and over pulley 49 and is provided at its end with a counter weight 57.

125 Pressure plate 52 carries a pair of trans-

versely extending bars 58 and 59 in spaced relation, bars 58 and 59 extending outwardly a short distance beyond the sides of header 7.

For the purpose of holding pressure plate 52 securely in position on header 7, I provide on end bars 1 and 2, a similar combination of parts which may best be understood by referring to Figure 2 which shows the parts carried on end frame 1 and it will be understood that the parts carried on end frame 2 are similar in construction and arrangement.

The parts just referred to are carried on and actuated through a shaft 60 having one end journaled in end frame 1 and having its other end journaled in end frame 2.

Referring to Figure 2, I provide on shaft 60 and keyed or otherwise secured thereto, a link 61. Link 61 is operatively connected to a second vertically extending link 62 which link 62 is in turn operatively connected to the lower end of a T-shaped pressure equalizer 63.

On one end of equalizer 63, I provide a pivotally mounted pressure link 64 adapted to be moved into and out of engagement with bar 59.

On the opposite end of equalizer 63 and pivotally mounted thereon, I provide a similar pressure link 65 adapted to move into and out of engagement with bar 58.

Pressure link 64 is mounted in a U-slot in the end of equalizer 63 as is also pressure link 65.

On Figure 2 I show pressure links 64 and 65 in heavy lines in engagement with bars 59 and 58 and I show in dotted lines, pressure links 64 and 65 disengaged from bars 58 and 59.

For the purpose of preventing the displacement of equalizer 63 when links 64 and 65 are out of engagement with bars 59 and 58, I provide a strap 66 (see Figure 5) which encircles equalizer 63 with its opposite ends secured to end frame 1 as by bolts 67.

On the opposite end of shaft 60, I provide a similar arrangement of parts comprising a link 68, link 69, equalizer 70 and pressure links 71 and 72 held in place by a strap 73.

On the end of shaft 60 adjacent end frame 2, I provide a vertically extending lever 74 having its lower end keyed or otherwise secured to shaft 60. On lever 74, I provide a latch 75 having a plurality, in this case shown as eight, notches 76 adapted to engage a bar 77 which extends laterally from header 7.

When it is desired to bring the pressure plate 52 into registration with header 7, pressure links 64, 65, 71 and 72 are placed into engagement with bars 58 and 59.

Latch 73 is then moved out of engagement with bar 77 and lever 74 is moved upwardly and inwardly in the direction of the arrow on Figure 2. This movement of lever 74 will cause the rotation of shaft 60 which in

turn will cause the outer ends of links 61 and 68 to be moved downwardly and this in turn will, through links 62 and 69 cause the downward movement of equalizers 63 and 70. The downward movement of equalizers 63 and 70 will in turn, through links 64, 65, 71 and 72 pull pressure plate 52 downwardly against header 7.

When the desired amount of pressure has been placed upon pressure plate 52, latch 75 is permitted to come into engagement with bar 77 to hold the parts in locked position.

When it is desired to raise the pressure plate 52 from header 7, the lever 74 is moved in the opposite direction which, through the rotation of shaft 60 and the actuation of links 61, 62, 68, and 79, will cause equalizers 63 and 70 to be moved upwardly to permit links 64, 65, 71 and 72 to be moved out of engagement with bars 58 and 59.

When the pressure plate 52 is moved downwardly into contact with the header 7, the pressure between the two will be equalized throughout the contacting surfaces due to the fact that the hinge 50 is a loose fit on its pivots permitting a limited angular movement of pressure plate 52 as the same is pulled downwardly by the pivoted equalizer 63 and 70.

Operation

When it is desired to subject skeins of textile material to the dyeing operation, the lever 20 is manipulated in the manner heretofore described to close valves 12 and to raise locating pins 14 and 14' above the surface of header 7.

The pressure plate 52 is then raised upwardly in the manner heretofore described to expose the upper face of header 7.

Skeins of textile material indicated at —a— on Figures 6 and 7 are then placed on header 7 by looping one end of a skein around a locating pin 14 and looping the other end of the skein around opposite locating pin 14'. The pressure plate is then moved downwardly and the pressure links 64, 65, 71 and 72 are placed in engagement with bars 58 and 59.

The lever 74 is then manipulated in the manner heretofore described to cause pressure plate 52 to be moved downwardly against header 7.

This operation will cause portions of the skeins of textile material to be gripped between the facings 10 on header 7 and the corresponding facings 54 on pressure plate 52.

Other portions of the yarn will be positioned in the openings 11, which openings 11 are in communication with troughs 8.

Dye, preferably extremely hot, is then introduced into the troughs 8 through the filling funnels 12 until the level of the dye reaches the top of the exposed portions of

70

95

100

105

110

115

120

125

130

the textile material which are positioned in the openings 11.

Additional dye is then introduced through the top of the openings 11 on to the top of the textile material there exposed. After the dye has been allowed to remain in contact with the textile material for the desired length of time, the lever 20 is manipulated in the manner heretofore described to open valves 13 and retract pins 14 and 14'.

Although I have not here shown any particular means for receiving the dye which will then be drained off from the troughs 8, it will be apparent that any convenient means may be employed, either conduits or open receptacles or troughs, et cetera.

The pressure plate 52 is then moved upwardly out of contact with header 7 and the dyed skeins of textile material are removed from header 7 and the operation is repeated with additional skeins of textile materials, if desired.

Referring to Figure 1, it will be noted that the openings 11 in trough 8 are in transversely staggered relation to the openings 11 in the next adjacent trough 8 and inasmuch as the skeins of textile material are positioned transversely of the header 7, the part of a skein which is over one trough 8 will be subjected to the action of the dye while the next adjacent portion of the same skein which is over the next adjacent trough 8 will be protected from the dye.

Similarly, it is desirable to have the openings 11 so arranged that only a portion of that part of a skein which is over a particular trough 8 will be subject to the action of the dye.

This particular arrangement of openings 11 in one trough 8 in relation to the openings 11 in the other trough 8 is not necessary but by using such an arrangement a random dyeing is obtained which will give a more desirable effect in the finished fabric.

Referring to Figure 9, it will be noted that the faces of the facings 10 and 54 are in angular relation to each other. With this arrangement of parts, the portion of a skein which is gripped between facings 10 and 54 will be gripped with increasing force from the edge of the openings 11 inwardly between the facings 10 and 54. This being the case, the dye in the openings 11 will affect, with diminishing intensity, the textile material between such facings 10 and 54 and will finally be unable to penetrate between such facings so that portions of such textile material will be entirely unaffected by the dye.

This results in yarn which is dyed with the full intensity of the dye in one place, but which will be dyed with diminishing intensity so that there will be obtained a "fading out" effect of such dyed portion.

I have shown in Figure 10, as illustrative

of the effect obtained in the finished fabric, a portion of such fabric, omitting for clarity most of the woof threads.

The main body portion 78 represents a fabric which has not been subjected to a dye whereas the striped portion 79 indicates that portion of the fabric which has been dyed, and it will be noted that such portions 79 are dyed more heavily in the middle and gradually diminish at each end until the dyed portion stops.

It will be understood that with the apparatus here disclosed, a skein of textile material may be subjected to the action of a single dye throughout the length of such skein if such is desired, but it will be also understood that it is possible to subject a single skein of textile material to as many different colored dyes as there are troughs provided in the dyeing apparatus.

In the apparatus here disclosed there are shown six troughs 8 which would permit the use of six different colors on a single skein, but obviously the apparatus can be constructed with a varied number of troughs so that as many different colors may be used as is desired.

It will also be understood that the facings 10 and 54 may be constructed to lie in parallel planes if the "fading out" effect in the finished fabric is not desired, although I prefer such "fading out" effect.

It will also be understood that modifications may be made in the specific means in which the skeins of textile material are subjected to the action of the dye, without departing from the spirit of my invention, for although I have shown and described a specific structure and form and relation of parts as an exemplification of an embodiment of my invention I do not desire to restrict myself to the exact size, shape and arrangement of parts of the apparatus disclosed nor do I desire to restrict myself to the precise way in which the skeins of textile material are subjected to the action of the dye, as various changes may be made within the scope of the appended claims.

I claim:

1. In a device of the class described, a main frame, a plurality of troughs having inclined bottoms carried by the frame, a drain valve at the lower end of each trough, operating means for all of said valves, a plurality of pressure plates adjacent the upper edges of the troughs, a plurality of other pressure plates removably positioned in registration with the first named pressure plates, and means for holding said plates in registration under pressure.

2. In a device of the class described, a main frame, a plurality of locating pins slidably mounted on the frame, means for reciprocating the pins vertically, a plurality of troughs carried by the frame, a plurality of pressure

plates adjacent the upper edges of the troughs, a plurality of other pressure plates removably positioned in registration with the first named pressure plates, and means for holding said plates in registration under pressure.

3. In a device of the class described, a main frame, a plurality of locating pins slidably mounted on the frame, means for reciprocating the pins vertically, a plurality of troughs carried by the frame, a plurality of pressure plates adjacent the upper edges of the troughs, a plurality of other pressure plates removably positioned in registration with the first named pressure plates with parts thereof in angular relation thereto, and means for holding said plates in registration under pressure.

4. In a device of the class described, a main frame, a plurality of troughs carried by the frame, a drain valve for each trough, means for simultaneously operating the valves, a plurality of pressure plates adjacent the upper edges of the troughs, a second frame hingedly mounted on the main frame, a plurality of pressure plates on the second named frame adapted to be moved into and out of registration with the first named pressure plates, and means for holding said pressure plates in registration under pressure.

5. In a device of the class described, a main frame, a plurality of troughs carried by the frame, a valve in each trough, means for simultaneously actuating the valves, a plurality of pressure plates adjacent the upper edges of the troughs, a plurality of other pressure plates removably positioned in registration with the first named pressure plates, and means for holding said plates in registration under pressure.

6. In a device of the class described, a main frame, a plurality of troughs carried by the frame, a valve on each trough, means for simultaneously actuating the valves, a plurality of locating pins slidably mounted on the frame, means for reciprocating the pins vertically, a plurality of pressure plates adjacent the upper edges of the troughs, a plurality of other pressure plates removably positioned in registration with the first named pressure plates, and means for holding said plates in registration under pressure.

7. In a device of the class described, a main frame, a plurality of troughs carried by the frame, a valve on each trough, means for simultaneously actuating the valves, a plurality of locating pins slidably mounted on the frame, means for reciprocating the pins vertically, a plurality of pressure plates adjacent the upper edges of the troughs, a plurality of other pressure plates removably positioned in registration with the first named pressure plates, in angular relation thereto, and means for holding said plates in registration under pressure.

8. In a dyeing machine, a dye trough, means at each edge of the trough for securing a skein of textile material transversely of the trough under gradually increasing pressure, means for introducing dye into the trough and drainage means for the trough.

In witness whereof I have hereunto set my hand.

JOSEPH A. FIRSCHING.
